DESIGN FOR A CONTAINER TO ENCLOSE A BOTTLE OR BOX

Martine Kane, New York, N. Y., assignor to Helena Rubinstein Inc., New York, N. Y., a corporation of New York

Application June 18, 1937, Serial No. 69,900

Term of patent 7 years

To all whom it may concern:

Be it known that I, Martine Kane, a citizen of the United States of America and residing in New York, New York, have invented a new, original, and ornamental Design for a Container to Enclose a Bottle or Box, of which the following is a specification, reference being had to the accompanying drawing, forming part thereof.

to enclose a bottle or box showing my new design, the container being closed.

I claim:—

The ornamental design for a container to enclose a bottle or box, as shown and described.

MARTINE KANE.
